(57) **CLAIM**

The ornamental design for a cannabis tool with a packing accessory, as shown and described.

DESCRIPTION

FIG. 1 is a first side view of the cannabis tool with a packing accessory, showing my new design,

FIG. 2 is a second side view of the same,

FIG. 3 is a bottom view of the same,

FIG. 4 is a top view of the same,

FIG. 5 is a first perspective view of the same,

FIG. 6 is a second perspective side view of the same,

FIG. 7 is a third perspective side view of the tool,

FIG. 8 is a fourth perspective side view of the same,

FIG. 9 is a first perspective side view of the tool without the packing accessory in the handle,

FIG. 10 is a side view of the same,

FIG. 11 is a side view of the packing accessory,

FIG. 12 is a top view of the same,

FIG. 13 is a bottom view of the same,

FIG. 14 is a first perspective view of the packing accessory,

FIG. 15 is second perspective view of the same,

FIG. 16 is a third perspective view of the same; and,

FIG. 17 is an exploded perspective view showing the cannabis tool and the packing accessory aligned for positioning within the handle thereof.
